INVISIBLE CUFF TACKER ATTACHMENT

Walter E. Mensching, Milwaukee, Wis.

Application July 21, 1953, Serial No. 369,388

4 Claims. (Cl. 112—178)

This invention relates in general to improvements in sewing machines, and more specifically to an invisible cuff tacker attachment.

The primary object of this invention is to provide an improved invisible cuff tacker attachment for blind-stitch sewing machines of the type disclosed in Patent No. 2,250,745, issued July 29, 1941, said attachment permitting the rendering of a feed dog on such a sewing machine inoperative whereby cuffs and the like may be tacked with such a sewing machine.

Another object of this invention is to provide an improved invisible cuff tacker attachment which may be conveniently attached to blind stitch sewing machines whereby the feed mechanism of the sewing machine may be selectively rendered operative or inoperative.

Another object of this invention is to provide an improved invisible cuff tacker attachment for a blind stitch sewing machine which is of a relatively simple construction and of a design whereby the same may be quickly and easily attached to existing blind stitch sewing machines with a minimum of modification to such machine.

A further object of this invention is to provide an improved adjustable spring connector, the spring connector being of a type whereby the spring may be selectively positioned in one of two positions, whereby the tension thereon may be selectively carried.

These together with other objects and advantages which will become subsequently apparent reside in the details of construction and operation as more fully hereinafter described and claimed, reference being had to the accompanying drawings forming a part hereof, wherein like numerals refer to like parts throughout, and in which:

Figure 1 is a vertical sectional view taken through a conventional blind stitch sewing machine and shows such a machine provided with the invisible cuff tacker attachment which is the subject of this invention and alternate position of the attachment being shown in dotted lines;

Figure 2 is a fragmentary vertical sectional view taken substantially upon the plane indicated by the section line 2—2 of Figure 1 and shows the general shape of a mounting plate of the attachment; and

Figure 3 is a perspective exploded view of adjustable spring connector means of the attachment.

Referring now to the drawings in detail, it will be seen that there is illustrated in Figure 1 a conventional blind stitch sewing machine of the type disclosed in Patent No. 2,250,745. The blind stitch sewing machine includes a plate 10, which has associated therewith a curved needle 12. Underlying the plate 10 is a pair of spaced turnable fingers 14 which are pivotally mounted as at 16. The turnable fingers 14 are intended to support portions of a garment 18 being stitched and are associated with a feed dog 20 for feeding the garment 18 beneath the needle 12.

In order that the left side of each of the turnable fingers 14 may be retained in the proper position, there is pivotally mounted as at 22 a rear body member 24 which has a transverse pin 26 on which there is pivotally mounted a rib member 27. The rib member 27 is con-

2

nected to an arm 28 of the rib body member 24 by a spring 30.

The sewing machine also includes an arm 32 which is pivotally mounted as at 34. The arm 32 includes a finger 36 which underlies the right side portion of each of the turnable fingers 14 to urge the same toward the feed dog 20. The arm 32 also includes a lower extension 38 which is normally spring urged to the right by a tension spring 40 which is connected to a work table

42. It will be understood that the springs 30 and 40 retain the turnable fingers 14 in the proper relation with respect to the plate 10 and the feed dog 20 so that the garment 18 being sewed by the needle 12 will be fed through the work area of the sewing machine at the proper rate.

The sewing machine illustrated in Figure 1 also includes other features necessary in the operation thereof, but playing no part in the present invention. Inasmuch as these features are clearly illustrated and described in Patent No. 2,250,745, it is not believed that further description thereof is necessary.

Inasmuch as the turnable fingers 14 are retained in associated relation with the feed dog 20, it will be seen that any garment, such as the garment 18 disposed therebetween will be automatically fed with respect to the needle 12. However, while this type of blind stitching is desired in many cases, in the cases of cuffs on men's pants, and the like, it is desired to place a plurality of stitches in one spot so as to be sure of the tacking and at the same time limit the area of the stitching. Inasmuch as the feed dog 20 would automatically feed the garment through the sewing machine, it will be seen that the sewing machine, as originally manufactured, would not be suitable for tacking of cuffs of trousers and the like.

In order that the sewing machine of Figure 1 may be converted to be selectively used as a blind stitch sewing machine or as an invisible cuff tacker, there has been provided the invisible cuff tacker attachment which is the subject of this invention, the attachment being referred to in general by the reference numeral 50. The attachment 50 includes a generally rectangular mounting plate 52, the mounting plate 52 is provided adjacent its upper edge with a pair of apertures 54 through which are received fasteners 56 which secure the upper portion of the mounting plate 52 to the work table 42. It will be understood that the mounting plate 52 is secured to a surface of the work table 42 remote from the extension 38 of the arm 32.

The mounting plate 52 is provided adjacent its lower edge with a pair of vertically extending rectangular openings 58. The openings 58 have extending therethrough legs 60 of a U-shaped spring connector member 62. The spring connector member 62 also includes a bight portion 64 which passes through a cam member 66. The cam member 66 is provided with an actuating arm 68 to facilitate positioning thereof. It will also be noted that the legs 60 are provided with enlarged hinge 70 to facilitate connection thereof to a pair of springs 40.

Inasmuch as the bight portion 64 of the spring connector member 62 is passed through the cam 66 eccentric of the center thereof, it will be seen that the effective length of the legs 60 of the spring connector member 62 may be varied, as is best illustrated in Figure 1. When the cam 66 is in the position best illustrated in forward lines in Figure 1, the tension of the spring 48 is to normal tension for the sewing machine in Figure 1 and the turnable fingers 14 will be positioned relative to the feet of 20 in the normal manner and the sewing machine will operate as originally designed. However, if the arms 68 of the cam 66 is swung to the dotted line position of Figure 1 the effective length of the leg 60 will be increased

with the result that they will move to their dotted line positions. This will reduce the tension on the springs 40 and permit the arm 32 to pivot about the pivot 34 and permit downward movement of the turnable fingers 14. When the turnable fingers 14 are in their lowermost positions, there will be sufficient room between the opposite surfaces of the turnable fingers 14 and the feed dog 20 for cuffs of pants, and the like, to be positioned for sewing by the curved needle 12. Inasmuch as the cuff of the pants will not be engaged by the feed dog 20, the 10 cuffs may be conveniently tacked with an invisible stitching, the only difference in the operation of the sewing machine being that the material being sewed is not advanced relative to the curved needle 12.

In order that the turnable fingers 14 may be properly 15 positioned relative to the feed dog 20, the extension 38 of the arm 32 is provided with an adjustable stop member 72. The stop member 72 is positioned to engage a portion of the work table 42 and limit swinging of the extension 38 to the right. By adjusting the effective length 20 of the stop member 72, the position of the turnable fingers 14 with respect to the feed dogs may be selectively varied.

From the foregoing, the construction and operation 25 of the device will be readily understood and further explanation is believed to be unnecessary. However, since numerous modifications and changes will readily occur to those skilled in the art, it is not desired to limit the invention to the exact construction shown and described, and accordingly all suitable modifications and equivalents 30 may be resorted to, falling within the scope of the appended claims.

What is claimed as new is as follows:

1. An attachment for a blind stitch sewing machine of the type having turnable fingers associated with a feed 35 dog and a control arm for said fingers, said turnable fingers being urged into position by a spring; said attachment comprising a mounting plate, an adjustable spring connector member, and a cam, said spring connector member being carried by said cam and passing through 40 said mounting plate, said spring being terminally connected to said spring connector member, said cam engaging said mounting plate and positioning said spring connector member relative thereto, said cam being movable to move said spring connector member through said 45 mounting plate to vary the effective length of said spring connector member relative to said mounting plate and selectively render said spring inoperative.

2. An attachment for a blind stitch sewing machine 50 of the type including a turnable finger for supporting material being sewn, a feed dog for feeding material over said turnable finger, a work table underlying said turnable finger, an arm mounted adjacent said work table, said arm having the intermediate portion thereof carried by a pivot thereby said arm pivots with respect to said work table, said arm having one end engaging said turnable finger to selectively retain said turnable finger in 55 operating relation with said feed dog, a spring, said spring connecting an opposite end of said arm to said work table, said spring through said arm spring urging said turnable finger into position with respect to said feed dog; said attachment comprising a mounting plate secura-

ble to said work table, a spring connector, and a cam, said spring connector being carried by said cam for adjustment relative to said mounting plate, said cam being engaged with said mounting plate and being movable to vary the effect of length of said spring connector member relative to said mounting plate to selectively render said spring inoperative whereby said arm permits said turnable finger to move out of cooperating relation with said feed dog.

3. An attachment for a blind stitch sewing machine of the type including a turnable finger for supporting material being sewn, a feed dog for feeding material over said turnable finger, a work table underlying said turnable finger, an arm mounted adjacent said work table, said arm having the intermediate portion thereof carried by a pivot thereby said arm pivots with respect to said work table, said arm having one end engaging said turnable finger to selectively retain said turnable finger in operating relation with said feed dog, a spring, said spring connecting an opposite end of said arm to said work table, said spring through said arm spring urging said turnable finger into position with respect to said feed dog; said attachment comprising a mounting plate securable to said work table, a spring connector, and a cam, said spring connector being carried by said cam for adjustment relative to said mounting plate, said cam being engaged with said mounting plate and being movable to vary the effect of length of said spring connector member relative to said mounting plate to selectively render said spring inoperative whereby said arm permits said turnable finger to move out of cooperating relation with said feed dog, adjustable stop means carried by said arm and engaged with said work table to limit movement of said turnable finger towards said feed dog.

4. An attachment for a blind stitch sewing machine of the type having turnable fingers, a feed dog, said turnable fingers being associated with said feed dog for positioning cloth to be sewed relative thereto, a pivotally mounted control arm having one end engaged with said finger, a spring connected to the other end of said control arm pivoting said control arm into engagement with said turnable fingers to retain said turnable fingers in operating relation with said feed dog, said attachment including a mounting plate, an adjustable spring connector member for anchoring said spring remote from said control arm, a cam, said spring connector member being U-shaped in outline and having spaced legs connected by a bight portion, said legs freely passing through said mounting plate and having terminal ends connected to said spring, said cam rotatably carrying said bight portion and engaging said mounting plate, said cam being movable to selectively vary the position of the terminal ends relative to said mounting plate whereby said spring may be selectively rendered inoperative.
